STENCILING APPARATUS

H. Russell Farwell, Quincy, Ill.

Application October 7, 1946, Serial No. 701,649

15 Claims. (Cl. 197—1)

1

This invention relates to a stenciling apparatus, and more particularly, to a stenciling apparatus in which a plurality of stencil frames supporting single-character stencils are so disposed that they may be readily utilized to stencil individually a plurality of characters on a desired object, to conform to any desired copy made up of such characters.

This invention is particularly applicable to the screen printing process, which is a widely used specialized form of stenciling. In the usual screen printing process, a stencil is prepared of the entire copy to be printed, on any particular object, such as a sign. This procedure is satisfactory where a large number of objects with identical copy are to be printed.

However, where it is desired to stencil a large number of objects, each with different copy, the silk screen method has heretofore been unsatisfactory, because of the necessity of preparing a separate over-all stencil for each object.

Nevertheless, it would be highly advantageous to be able to utilize the silk screen type of stencil in such printing operations, since the finished product in a screen printing operation has many desirable qualities, such as uniformity of characters, long life, and the like.

It would be possible to use such stencils where the copy varies on each object stenciled, if each stencil were prepared to include only one character, so that each individual character in the desired copy could be stenciled separately in the proper sequence and alignment. To merely have a number of single-character stencils available for selection and use would not, however, be commercially feasible in most printing operations. To successively select each separate stencil frame and stencil from a rack, to align it on the object being stenciled, and then to perform the actual stenciling operation, all entirely by hand, would be exceedingly cumbersome and time consuming, and would have very little advantage, if any, over a hand lettering process.

It is therefore an object of this invention to provide a stenciling apparatus, utilizing a plurality of single-character stencils, which provides a means of quickly and accurately stenciling individual characters in the proper order and alignment to conform to any desired copy on an object properly disposed thereon.

It is a further object to provide a stenciling apparatus which has a movable printing base adapted to support an object to be stenciled, which base automatically moves the required dis-

2

tance between individual characters, as each stencil is moved out of contact with the object being stenciled.

It is an additional object to provide a stenciling apparatus which utilizes a plurality of single-character stencils which are normally disposed in spaced relation of a printing base, but which may be individually moved into contact with the object to be stenciled on the printing base, so that any desired combination of stenciled characters may readily be formed.

It is still another object to provide a stenciling apparatus in which all spacing between individual characters is produced automatically; in which the stencils and their supporting frames are easily and quickly removed for servicing or replacement; which is particularly adapted to the use of silk screen stencils which are very desirable for particular types of work; which is simple in construction and operation; which may be produced at a relatively low cost; which forms each character in a uniform and accurate manner; which can produce a volume of signs, for instance, each with different copy, at a fraction of the cost of printing them with type; and which can print at a much faster rate than normal hand lettering can be accomplished, and therefore at a much lower cost.

Further objects and advantages of this invention will become evident as the description proceeds and from an examination of the accompanying drawings which illustrate one embodiment of the invention and in which similar numerals refer to similar parts throughout the several views.

In the drawings:

Figure 1 is a perspective view of a stenciling apparatus embodying the invention;

Figure 2 is a fragmentary view in elevation, and partly in cross section, showing the stenciling base, the escapement mechanism, and the stencil frame supporting means in more detail;

Figure 3 is a fragmentary plan view from above showing one of the stencil frames in aligned position; and,

Figure 4 is a fragmentary view, in elevation and partly in cross section, looking toward the rear of the apparatus shown in Figure 1 and showing the printing base and escapement mechanism in more detail.

Referring now to Figure 1 the supporting frame 10 which may be of any suitable table-like construction, has the two grooved guide rails 12 and 14 supported thereon by the longitudinal cross

bars 16 and 18. The printing base 20 has the supporting rollers 22 fixed thereto, the rollers being positioned to ride within the grooved guide rails 12 and 14 and to allow the printing base 20 to move longitudinally in a guided path within the limits of the stop 24 and the lateral cross bar 26.

Rotatably supported above the printing base 20 and the guide rails 12 and 14 are the stencil frames 28 which are disposed radially about the hub 38 (Figure 2) and normally form a shallow, inverted cone. Fixed to the longitudinal cross bar 18 is the guide member 32, having the slot 34 therein. As shown in Figures 2 and 3, this slot is adapted to receive the outer end 27 of any one of the stencil frames 28 after it has been properly aligned with respect to the slot 34, and is depressed. The method of supporting the frames 28 is shown in detail in Figure 2. The wheel-like member 36 is rotatably disposed on the hollow shaft 38 which is in turn non-rotatably supported by the longitudinal cross bar 40. The cross bar 40 is supported by two right angle supports 42 secured to the rear of the supporting frame 10, and the shaft 38 is secured to the cross bar 40 by the nut 41. The wheel member 36 has the rim 44 formed along its peripheral edge, and the shaft 38 has the hub 39 formed at its upper extremity. Each of the frames 28 has a yoke 48 secured thereto which is adapted to receive the edge of the rim 44. The yokes 48 are secured to the frames 28 at points which will allow the inner end 29 of each frame to be inserted beneath the hub 39 on the shaft 38 when the frames are put in place on the rim 44.

The rod 50 is disposed within the hollow shaft 38, and has the flange 52 at its upper extremity which normally rests on the hub 39. The lug 54 formed as an integral part of the flange 52 normally projects into the wedge shaped slot 56 in the hub 39, the bottom of the lug being substantially flush with the bottom of the hub when the flange is resting on the hub. The slot 56 is centered about the axis of the slot 34 in the guide member 32, which axis is perpendicular to the line of movement of the printing base 20. In addition, the dimensions of the slot 56 are such that any one of the inner ends 29 of the frames 28, which are normally overlapped by the hub 39, will, when properly aligned therewith, be received by that slot. Consequently, since the slot 34 and the slot 56 are aligned on the same axis, when a stencil frame is aligned with either one of the slots, it will also be aligned with the other. This, in turn, means that when the inner end 29 of a particular frame is aligned with the slot 56, the outer end 27 may be depressed sufficiently to enter into the slot 34, and the inner end 29 will simultaneously enter into the slot 56, the stencil frame pivoting on the yoke 48 about the rim 44. As the inner end 29 of one of the stencil frames is moved into the slot 56, the lug 54 will be forced upward, which will in turn cause the flange 52 and the rod 50 to move upwardly. To insure that the lug 54 does not get out of alignment with respect to the slot 56, the pin 58 is carried by the hub 39 and extends through an opening in the flange 52, allowing a vertical movement of the flange but no rotary movement.

Since the wheel member 36 is free to rotate about the shaft 44 when a complete set of stencil frames is inserted in place, as described and as shown in Figure 1, any one of the stencil frames may be easily rotated into alignment with the slots 34 and 56. The complete set of frames will rotate as a unit since their inner ends are sub-

stantially contiguous and there is sufficient friction between the yokes 48 and the rim 44 of the wheel to cause both the stencil frames and the wheel to rotate together. Also, the inner ends 29 of the stencil frames will rotate freely past the slot 56 when there is no downward pressure applied to their outer ends 27, since the bottom surface of the lug 54 is normally flush with the bottom surface of the hub 39. As shown in Figure 2, the rim 44 and the upper surface of the printing base 20 are in substantially the same plane, so that when one of the stencil frames is aligned as described and then depressed, the base of the outer end 27 of the stencil frame will be substantially flush with the upper surface of the printing base. The outer end 27 of each stencil frame has the rectangular opening 62 therein across which is supported a stencil 64, preferably of the silk screen type. The stencil itself is disposed on the bottom surface of the stencil frame and, therefore, will be flush with the printing base or any object supported thereon when the stencil frame is depressed as described above.

To aid in the operation of the apparatus, the stencil frames each have a reproduction 67 of the particular character which the attached stencil describes fixed thereon as shown in Figures 1 and 3. The desired stencils can be successively moved into stenciling position in an efficient and rapid manner, with the aid of these visible means of identifying the appropriate stencil frames.

As previously mentioned and as shown in Figure 2, the rod 50 extends through the hollow shaft 38 and projects beyond the end of the shaft 38 carrying the nut 41. This end of the rod has secured thereto the socket member 66 adapted to cooperate with the forked member 68 which is carried by the arm 70 which is pivoted to an extension 72 of the frame 10 as at 74. At the opposite end the arm 70 is linked to a second arm 76 by the link 78, the two arms being rotatably secured to the link 72 at 80 and 82, respectively.

The arm 76 is fixed to the dog-supporting member 84 which is a part of the escapement mechanism which controls the position of the printing base during operation of the apparatus. This escapement mechanism is shown in detail in Figures 2 and 4. The dog-supporting member 84 is pivotally mounted on one end of the supporting arm 86, as at 88. The opposite end of the supporting arm 86 is secured to the supporting bar 90 which is, in turn, pivotally secured along one of its longitudinal edges to the frame 10, as at 92 and 94. A control arm 96 is also secured to the bar 90 as shown in Figures 1 and 4, and extends out into operable position with respect to the operator of the apparatus.

The dog-supporting member 84 is L-shaped and carries one fixed dog 98 which is secured to the side 100 of the supporting member 84, and projects beyond the top of the side 100. The dog 102 is pivotally secured at the inner corner 104 of the L-shaped member 84 and normally is held away from the side 100 by the spring 106 and against the stop 108. The printing base 20 has the row of equally spaced teeth 110 secured to the bottom surface in a line parallel to the line of movement of the base 20. These teeth are placed directly above the dog-supporting member 84 and positioned so that they will intercept the dog 102 when the rod 50 and the various parts connected thereto are all in their normal positions. This is the position illustrated in Figure 2. The spacing between the

teeth 110 corresponds to the spacing desired between characters, and is adjusted to the size of the characters which are formed by the stencils. These teeth 110 and the series of cooperating members just described which culminates in the dogs 98 and 102 which are adapted to cooperate with the teeth 110, form the escapement mechanism referred to above.

This escapement mechanism serves to automatically control the spacing of the printing base 20, the base being moved a predetermined distance between the alignment of each stencil. The motive power for moving the printing base 20 when the escapement mechanism is operated, is supplied by the weight and pulley arrangement shown in Figure 1. The weight 116 is suspended on the cable 118 which travels over the pulley 120 and is secured to the left end of the printing base. This arrangement serves to urge the printing base toward the left end of the rails 12 and 14, and it will move in that direction unless held against such movement by the escapement mechanism. This movement of the base, of course, also serves to shift the object receiving the stenciling a predetermined distance in relation to the aligning slot 34 so that the various stencil frames and stencils are moved into contact with the object being stenciled at regularly spaced intervals.

With the outer ends of the stencil frames all in the normal raised position shown in Figure 1, and with the rod 50 therefor in the normal up-raised position so that the flange 52 is flush against the hub 30, the dog-supporting member 84 is maintained in the position shown in Figure 2, so that one of the teeth 110 intercepts the movable dog 102 and carries it back against the side 100. The printing base 20 is thus normally maintained in a stationary position.

When the desired stencil frame is moved into alignment with the slot 34 and is then depressed so that the end 27 of the stencil frame enters into that slot and comes to rest against the object carried by the printing base, the stencil frame will pivot about the yoke 48 and the opposite end 29 of the frame will move upwardly into the slot 56 in the hub 30, carrying the lug 54 with it. This, in turn, will raise the flange 52, which will cause the rod 50 to rise within the shaft 38. This upward movement of the rod 50 will cause the arm 70 to pivot upwardly about the point 74, and this movement will be transmitted through the link 78 to the arm 76 which is rigidly fixed to the dog-supporting member 84. Since this member is pivoted at 88 on the arm 86, it will be tilted in a counterclockwise direction by an upward movement of the lower end of the arm 76.

Such a tilting movement of the member 84 will cause the dog 102 to disengage from the tooth 111. However, prior to the time this disengagement becomes complete the stationary dog 98 has moved, with the tilting of the member 84, into engagement with the same tooth 111. Consequently, the dog 102 is released and is immediately pulled back against the stop 108, as shown in Figure 4, by the spring 106.

After the desired character has been stenciled on the object carried by the printing base, by the use of the applicator 112 (Figure 1) which normally rests in the holder 114, the stencil frame is released and returns to its normal position. As the frame is allowed to return to its normal position, its end 29 moves down, the flange 46 and the rod 50 also move down, as does the arm 76

70 and the lower end of arm 76, all of which causes the dog-supporting member 84 to tilt back to its original position. This movement of the member 84 causes the dog 98 to disengage from the tooth 111, and also brings the dog 102 back into the line of the teeth 110, although it is now out of position to intercept the tooth 111, since it has been drawn back by the spring 106.

The printing base 20 is, as mentioned above, at all times subjected to a pulling force from right to left (Figure 1) by the suspended weight 116 shown in Figure 1, and the cable 118 and pulley 120 cooperating therewith. This force will, of course, tend to move the printing base 15 from right to left whenever it is not held stationary. Therefore, when the dog 98 is disengaged from the tooth 111, as described, the printing base 20 will move from right to left until the tooth 113, which will engage the dog 102 as the base so moves, brings that dog up against the side 100 of the dog-supporting base. The distance of this movement will normally be the distance between the corresponding faces of two adjacent teeth such as 111 and 113. Such repeated movement of the base 20 and the corresponding spacing of the stenciled letters will take place as the various stencils desired are applied, until the base 20 comes to rest against the stop 24.

30 In order to allow the printing base to be returned to the starting position, it is necessary to have some means of removing the dogs 98 and 102 from the line of movement of the teeth 110. This is accomplished in the embodiment of the invention illustrated by mounting the dog-supporting member 84 on the supporting arm 86 which is in turn mounted on the bar 90 which has its lower longitudinal edge pivotally mounted on the frame 10 of the apparatus. This arrangement allows the arm 86 and the member 84 to be moved downward at will, which will, of course, move the dogs 98 and 102 out of engagement with the teeth 110. The bar 90 is normally held in a position which maintains the escapement mechanism in operating position by the spring member 122, shown in Figure 1, which is secured to the outer end 126 of the control arm 96. The outer end 126 of the arm 96 is normally held against the stop 128 by this spring member 112, but it may readily be moved in a downward direction by the operator to allow the printing base to be moved freely to whatever position is desired, either by hand, or by the suspended weight and pulley arrangement described.

35 The embodiment of the invention shown in Figure 1 also has incorporated therein the supporting stand 130 to hold a card or similar device containing the copy which is to be placed on the object to be stenciled. This stand may be conveniently placed on the pin 58. The rule 132 may also be mounted on the cross bar 18 to serve as a guide when aligning the object to be stenciled on the printing base 20.

40 Also, as shown in Figure 4, a clamping means such as the steel clip 134 is desirable to hold the object being stenciled in place on the printing base during the stenciling operation. In Figure 1 a sign 136 made of sheet metal is shown in stenciling position on the printing base 20, being held in such position by the clip 134.

45 As is evident from the detailed discussion above, there are numerous advantages embodied in a stenciling apparatus incorporating this invention. The flexibility of the device is one of the most important, since almost any type of copy

may be rapidly and easily stenciled on the desired object. Since the stencil frames are merely frictionally held in place, they may be quickly removed for servicing or replacement, which also allows the ready insertion of a completely different set of stencils when desired.

In actual operation the operator first places the material to be stenciled, such as a sign, on the printing base. After properly adjusting the position of the material with reference to the marginal limits of the base with the aid of the rule 132, the operator manually pushes the printing base into the proper starting position. Using the copy held by the supporting device 130 as a guide, the operator selects the stencil frame containing the first character to be stenciled, and the circle of stencil frames surrounding the hub 30 is rotated until that stencil frame is disposed directly above the slot 34. This stencil frame is then pushed down into the slot 34 so that it rests on the material to be stenciled, which is carried by the printing base. This operation is carried out entirely with the left hand.

The operator then makes one stroke with the applicator 112, held in his right hand, across the stencil 64 which is stretched across the bottom of the rectangular opening 62 in the stencil frame 28, and is now flush against the object being stenciled. The stencil frame is then immediately released and will automatically regain its normal position in the circle of stenciling frames. At the same time the printing base will automatically move one space to the left, so that the material being stenciled is in the proper position to receive the next character. This procedure is continued, stenciling one character at a time until the desired copy has been transcribed onto the material held by the printing base.

The apparatus is so simple in operation that the average operator after a minimum amount of experience is ordinarily capable of lettering several hundred signs, or the like, per day, even though each sign is stenciled with different copy. The normal stenciling rate of an experienced operator has been found to be about twenty-five characters per minute. This rate of stenciling is much faster than the usual rate of hand lettering done with a brush, and consequently the stenciling process is considerably less expensive.

Another advantage of this apparatus over hand lettering is that each character is stenciled in a completely uniform manner, which characteristic makes the resultant product both more pleasing to the eye and more wear resistant.

The drawings in the above discussion are not intended to represent the only possible form of this invention in regard to the details of construction. Changes in form and in the proportion of parts, as well as the substitution of equivalents, are contemplated, as circumstances may suggest or render expedient without departing from the spirit or scope of this invention.

I claim:

1. A stenciling apparatus comprising a supporting frame, a stenciling base movably disposed on said supporting frame, said stenciling base being adapted to support an object to be stenciled, a shaft disposed on said frame, a hub member disposed on one end of said shaft, a radial slot in said hub member, a wheel-like member rotatably disposed on said shaft in spaced relation to said hub member, and a plurality of stencil frames disposed radially about said hub member, said hub member overlapping the inner ends of said stencil frames, said sten-

cil frames being pivotally disposed on the peripheral edge of said wheel-like member and being rotatable therewith about said hub member, said shaft and said radial slot in said hub member being so positioned in relation to said stenciling base that said stencil frames may be moved individually into contact with an object supported by said stenciling base when properly aligned with said base.

- 10 2. A stenciling apparatus comprising a supporting frame, a stenciling base movably disposed on said supporting frame, said stenciling base being adapted to support an object to be stenciled, a shaft disposed on said frame, a hub member disposed on one end of said shaft, a radial slot in said hub member, a wheel-like member rotatably disposed on said shaft in spaced relation to said hub member, a plurality of stencil frames disposed radially about said hub member, said hub member overlapping the inner ends of said stencil frames, said stencil frames being pivotally disposed on the peripheral edge of said wheel-like member and being rotatable therewith about said hub member, said shaft and said radial slot in said hub member being so positioned in relation to said stenciling base that said stencil frames may be moved individually into contact with an object supported by said stenciling base when properly aligned with said base, and means actuated by any stencil frame so moved adapted to change the position of said stenciling base as said stencil frames are released from contact with said object.
- 35 3. A stenciling apparatus comprising a supporting frame, a stenciling base movably disposed on said supporting frame, said stenciling base being adapted to support an object to be stenciled, a non-rotatable shaft having a longitudinal bore therethrough disposed on said frame, a hub member disposed at one end of said shaft, a radial slot in said hub member substantially perpendicular to the longitudinal axis of said stenciling base, a wheel-like member rotatably disposed on said shaft in spaced relation to said hub member, a plurality of stencil frames disposed radially about said hub member, said hub member overlapping the inner ends of said stencil frames, said stencil frames being pivotally disposed on the peripheral edge of said wheel-like member and being rotatable therewith about said hub member, a non-rotatable rod disposed within said longitudinal bore in said shaft being longitudinally movable therein, a disc-like flange disposed on the end of said rod adjacent said hub member and adapted to normally rest on said hub member, and a lug on said disc-like flange normally projecting into said slot in said hub member and being substantially flush with the opposite side of said hub member, said slot being adapted to allow the inner end of any one of said stencil frames to enter therein when said stencil frame is properly aligned with respect to said slot, said inner ends of said stencil frames being adapted to displace said lug in said slot when pivoted about the peripheral edge of said wheel-like member, said shaft being so positioned in relation to said stenciling base that said stencil frames may be moved individually into contact with an object supported by said stenciling base when properly aligned with said base, and with said slot, said displacement of said lug causing said disc-like flange to move said rod longitudinally in said shaft, and means cooperating with said rod adapted to change the

position of said stenciling base as said stencil frames are released from contact with said object.

4. A stenciling apparatus comprising a supporting frame, a stenciling base movably disposed on said supporting frame, said stenciling base being adapted to support an object to be stenciled, a non-rotatable shaft having a longitudinal bore therethrough disposed on said frame, a hub member disposed at one end of said shaft, a radial slot in said hub member substantially perpendicular to the longitudinal axis of said stenciling base, a wheel-like member rotatably disposed on said shaft in spaced relation to said hub member, a plurality of stencil frames disposed radially about said hub member, said hub member overlapping the inner ends of said stencil frames, said stencil frames being pivotally disposed on the peripheral edge of said wheel-like member and being rotatable therewith about said hub member, a non-rotatable rod disposed within said longitudinal bore in said shaft, being longitudinally movable therein, a disc-like flange disposed on the end of said rod adjacent said hub member and adapted to normally rest on said hub member, a lug on said disc-like flange normally projecting into said slot in said hub member and being substantially flush with the opposite side of said hub member, said slot being adapted to allow the inner end of each stencil frame to enter therein when each said stencil frame is properly aligned with respect to said slot, said inner ends of said stencil frames being adapted to displace said lug in said slot when pivoted about the peripheral edge of said wheel-like member, said shaft being so positioned in relation to said stenciling base that said stencil frames may be moved individually into contact with an object supported by said stenciling base when properly aligned with said base and with said slot, said displacement of said lug causing said disc-like flange to move said rod longitudinally in said shaft, a lever pivoted on said supporting frame adapted to cooperate with said rod, a supporting bar pivotally disposed on said supporting frame, a control member disposed on said supporting bar, a supporting arm on said supporting bar, an escapement member pivotally disposed on said arm, a second arm disposed on said escapement member adapted to cooperate with said lever, a series of spaced stop lugs on said stenciling base, and means normally urging said escapement member into contact with one of said stop members, said escapement member being adapted to be activated by the movement of said rod, lever, and second arm to allow one of said stop members to escape, said escapement member also being adapted to be moved out of contact entirely with said stop members by a movement of said control member, supporting bar, and supporting arm.

5. A stenciling apparatus comprising a supporting frame, a stenciling base movably disposed on said frame, a plurality of stencil frames movably disposed on said frame, said stencil frames being adapted to be moved individually at will into contact with an object supported by said stenciling base, a supporting bar pivotally disposed on said supporting frame, a control member disposed on said supporting bar, a supporting arm disposed on said supporting bar, a dog-supporting member pivotally disposed on said supporting arm, a stationary dog disposed on said dog-supporting member, a second dog pivotally disposed on said dog-supporting member, a stop lug disposed on said dog-

10 supporting member and adapted to limit the movement of said second dog, means urging said second dog toward said stop lug, a control arm disposed on said dog-supporting member adapted to cooperate with means connecting said arm to said stencil frames, and a series of stop members disposed on said stenciling base adapted to cooperate with said dogs.

6. In a stenciling apparatus of the character described, an escapement means comprising a pivotally disposed supporting bar, a control member adapted to cooperate with said supporting bar, a supporting arm disposed on said supporting bar, a dog-supporting member pivotally disposed on said supporting arm, a stationary dog disposed on said dog-supporting member, a second dog pivotally disposed on said dog-supporting member is spaced relation to said stationary dog, a stop lug disposed on said dog-supporting member and adapted to limit the movement of said second dog, means urging said second dog toward said stop lug, and a control arm disposed on said dog-supporting member adapted to cause said member to move in relation to said supporting arm.

7. In a stenciling apparatus of the character described having an escapement mechanism, a stencil frame assembly comprising a non-rotatable hollow shaft having a longitudinal bore therethrough, a hub member disposed on one end of said shaft, a radial slot in said hub member, a wheel-like member rotatably disposed on said shaft in spaced relation to said hub member, a plurality of stencil frames radially disposed about said shaft, said hub member overlapping the inner ends of said stencil frames and said stencil frames being pivotally disposed on the peripheral edge of said wheel-like member and being rotatable with said wheel-like member about said hub member, a non-rotatable rod disposed within said shaft being longitudinally movable therein, a disc-like flange disposed on the end of said rod adjacent said hub member, said flange being adapted to normally rest on said hub member, and a lug on said disc-like flange normally projecting into one side of said slot in said hub member and being substantially flush with the opposite side of said hub member, said slot being adapted to allow the inner end of any one of said stencil frames to enter therein when said stencil frame is rotated into substantial alignment with said slot and thereafter pivoted, said inner end of said stencil frame when so aligned and so pivoted being adapted to displace said lug in said slot which, in turn, causes said flange to be displaced, and said rod to move longitudinally within said shaft, such movement of said rod being adapted to actuate said escapement mechanism.

8. In a stenciling apparatus of the character described having an escapement mechanism, a stencil frame assembly comprising a non-rotatable shaft, a hub member disposed on one end of said shaft, a radial slot in said hub member, a wheel-like member rotatably disposed on said shaft, a plurality of stencil frames radially disposed about said shaft, said hub member overlapping the inner ends of said stencil frames and said stencil frames being pivotally disposed on said wheel-like member and being rotatable with said wheel-like member about said hub member, means normally disposed in said slot adapted to be moved by the inner end of one of said stencil frames when said stencil frame is pivoted on said wheel-like member, after having been rotated into substantial alignment with

11

said slot, and means cooperating with said last named means adapted to move longitudinally within said non-rotatable shaft and to operate said escapement mechanism.

9. A stenciling apparatus comprising a supporting frame, a stenciling base movably disposed on said supporting frame, said stenciling base being adapted to support an object to be stenciled, a plurality of radially disposed stencil frames capable of rotation as a unit about a central point, and means normally preventing movement of the stencil frames toward said stenciling base but permitting the individual pivoting of said stencil frames about a point intermediate their ends toward said stenciling base when said frames are individually moved into a predetermined position with relation to said stenciling base.

10. A stenciling apparatus comprising a supporting frame, a stenciling base movably disposed on said supporting frame, said stenciling base being adapted to support an object to be stenciled, a plurality of radially disposed stencil frames capable of rotation as a unit about a central point, means normally preventing movement of the stencil frames toward said stenciling base but permitting the individual pivoting of said stencil frames about a point intermediate their ends toward said stenciling base when said frames are individually moved into a predetermined position with relation to said stenciling base, and means cooperating with each stencil frame so moved toward said stenciling base adapted to change the position of said stenciling base as said stencil frames are released from contact with said object.

11. A stenciling apparatus comprising a supporting frame, a stenciling base movably disposed on said supporting frame, said stenciling base being adapted to support an object to be stenciled, a plurality of radially disposed stencil frames capable of rotation as a unit about a central point, means normally preventing movement of the stencil frames toward said stenciling base but permitting movement of each of said stencil frames, one at a time, toward said stenciling base when said frames are individually moved into a predetermined position with relation to said stenciling base, means cooperating with each stencil frame so moved toward said stenciling base activating a lever pivoted on said supporting frame, a supporting bar pivotally disposed on said supporting frame, a control member disposed on said supporting bar, a supporting arm on said supporting bar, an escapement member pivotally disposed on said arm, a second arm disposed on said escapement member adapted to cooperate with said lever, a series of spaced stop lugs on said stenciling base, and means urging said escapement member into contact with one of said stop members, said escapement member being adapted to be activated by movement of said second arm to allow one of said stop members to escape, said escapement member also being adapted to be moved out of contact entirely with said stop members by a movement of said control member, supporting bar and supporting arm.

12. In a stenciling apparatus of the character described, the combination of a hub member having a radial slot therein, a plurality of remov-

able stencil frames radially disposed about and overlapped by said hub member, and a rotatable circular support member disposed in spaced relation to said hub member and forming a fulcrum about which said stencil frames may be pivoted when respectively aligned with said slot.

13. In a stenciling apparatus of the character described, the combination of a flanged sleeve, said sleeve having a radial slot in the flanged portion thereof, a rod slidably mounted in said sleeve, a flange on said rod adapted to normally abut the flanged portion of said sleeve, a plurality of removable stencil frames radially disposed about and overlapped by said flanged portion of said sleeve, and a rotatable circular support member disposed in spaced relation to said sleeve and forming a fulcrum about which said stencil frames may be pivoted when respectively aligned with said slot.

14. In a stenciling apparatus of the character described having a movable stenciling base, the combination of a flanged sleeve, said sleeve having a radial slot in the flanged portion thereof, a rod slidably mounted in said sleeve, a flange on said rod adapted to normally abut the flanged portion of said sleeve, a plurality of removable stencil frames radially disposed about and overlapped by said flanged portion of said sleeve, and a rotatable circular support member disposed in spaced relation to said sleeve and forming a fulcrum about which each of said stencil frames when properly aligned with said slot is capable of being individually pivoted so as to be moved into contact with said stenciling base and to simultaneously move said rod longitudinally, and means cooperating with said rod adapted to change the position of said stenciling base.

15. In a stenciling apparatus of the character described having a movable stenciling base, the combination of a hub member having a radial slot therein, a plurality of removable stencil frames radially disposed about and overlapped by said hub member, a rotatable circular support member disposed in spaced relation to said hub member and forming a fulcrum about which each of said stencil frames when aligned with said slot is capable of being individually pivoted so as to be moved into contact with said stenciling base, and means cooperating with said stencil frames when so pivoted adapted to change the position of said stenciling base.

H. RUSSELL FARWELL.
